UNITED STATES PATENT OFFICE

FRANK SCHAEFER, OF KALAMAZOO, MICHIGAN, ASSIGNOR OF ONE-HALF TO AMERICAN SIGNS CORPORATION, OF KALAMAZOO, MICHIGAN

GASEOUS TUBE LAMP SIGN

Application filed August 17, 1928. Serial No. 300,341.

The main objects of this invention are:

First, to provide an improved gaseous tube lamp sign in which the assembled tube structure constitutes a complete sign other than 5 the matter of housing or mounting.

Second, to provide a gaseous tube lamp structure having storage or reserve gas chambers of substantial capacity.

Third, to provide a gaseous tube sign in 10 which the character or indicia element is effectively supported on a body element of substantial size which constitutes an effective supporting base.

Fourth, to provide a gaseous tube lamp in 15 which the electrical connectors are effectively housed and permit the making of the electrical connections without likelihood of injury to the lamp.

Objects relating to details and economies 20 of my invention will appear from the description to follow. The invention is defined and pointed out in the claims.

A structure which is a preferred embodiment of my invention is illustrated in the accompanying drawings, forming a part of this 25 application, in which:

Fig. 1 is an elevation of a structure embodying the features of my invention, a portion of one of the electrode chamber housings 30 being broken away and sectioned.

Fig. 2 is a fragmentary view mainly in longitudinal section.

Fig. 3 is an elevation of a complete structure, the portions which are coated to render 35 opaque in practice being indicated by cross hatching.

In the drawings similar reference characters refer to similar parts throughout the several views.

As embodied in the accompanying drawings, my improvements consist of a tubular body member 1 having a central partition 2 therein providing a pair of gas chambers 3. The outer ends of this body member are reduced at 4 providing electrode chambers for 45 the electrodes 5. These electrodes have external contact members 6.

The housings 7, preferably of glass or other insulating material, are of approximately 50 the same diameter as the body member 1 and

are adapted to abut against the shoulder 8 formed by the reduced extensions 4. These housings are provided with lugs 9 while the body member has opposed lugs 10 with which the connecting springs 11 are engaged, there- 55 by securing the housings to the body member.

Coiled spring connectors 12 are arranged in the outer ends of these housings and electrically connected to the binding post 13 for the circuit wires 15.

Arms 16 are connected to the body member adjacent the outer ends of the chambers 3, these arms constituting connections and supports for the indicia or character element 17 which is formed of a glass tube, the ends of the tube being connected to the outer ends of the arms, thereby providing a continuous passage for the gas and at the same time supporting the indicia element or illuminating portion of the lamp. 70

The remaining portions of the lamp are preferably coated with black paint to render them opaque, as is indicated in Fig. 3.

My improved lamp is simple and economical in its parts; the body member constitutes 75 a support and bracing means for the more delicate character or illuminating element of the lamp and very materially increases the gas capacity of the lamp.

The diameter of the body member is con- 80 siderably greater than that of the character element and may be readily mounted or supported to carry the more delicate character element.

I have not illustrated the supporting means 85 as they form no part of this invention.

Having thus described my invention, what I claim as new and desire to secure by Letters Patent, is:

1. A structure of the class described comprising a tubular body member having reduced electrode chambers at its ends and a central partition providing a pair of gas chambers, tubular arms adjacent the ends of said body communicating with said gas chambers, a tubular indicia element connected at its ends to the upper ends of said arms and opening thereto, electrodes disposed in said electrode chambers and provided with external contacts, tubular hous- 90 95 100

- ings of a diameter corresponding to that of said body member arranged to embrace said electrode chambers, lugs on said body member and housings, coiled springs engaging said lugs whereby said housings are supported on the ends of said body member, spring circuit connectors arranged in said housings to coact with said circuit contacts when the housings are mounted on said body member, and binding posts on the outer ends of said housings electrically connected to said connectors. 6. A gaseous tube lamp comprising a tubular body member partitioned to provide a pair of gas chambers, a tubular indicia element connected at its ends to said gas chambers adjacent the outer ends thereof, and electrodes disposed at the outer ends of said body member. 70
2. A structure of the class described comprising a tubular body member having reduced electrode chambers at its ends and a central partition providing a pair of gas chambers, tubular arms adjacent the ends of said body member communicating with said gas chambers, a tubular indicia element connected at its ends to the upper ends of said arms and opening thereto, electrodes disposed in said electrode chambers and provided with external contacts, tubular housings of a diameter corresponding to that of said body member arranged to embrace said electrode chambers, spring circuit connectors arranged in said housings to coact with said circuit contacts when the housings are mounted on said body member, and binding posts on the outer ends of said housings electrically connected to said connectors. 75
3. A structure of the class described comprising a tubular member having reduced electrode chambers at the ends thereof, electrodes disposed in said chambers and provided with external contacts, tubular housings of a diameter corresponding to that of said member arranged to embrace said electrode chambers, lugs on said member and housings, coiled springs engaging said lugs whereby said housings are supported on said member, and spring circuit connectors arranged in said housings to coact with said circuit contacts when the housings are mounted on said member. 80
4. A gaseous tube lamp comprising a tubular body member partitioned to provide a pair of gas chambers, tubular arms adjacent the ends of said body member communicating with said gas chambers, a tubular indicia element connected at its ends to the outer ends of said arms and opening thereto, said indicia element being supported by said arms, and electrodes disposed at the ends of said body member. 85
5. In a gaseous tube lamp, the combination of a tubular body member partitioned to provide a pair of gas chambers, a tubular illuminating element connected at its ends to said gas chambers and disposed at one side of said body member whereby said body member constitutes a support for said illuminating element, and electrodes disposed in said body member outwardly beyond the points of connection of said illuminating member to said body member. 90
- In witness whereof I have hereunto set my hand. 95
